UNITED STATES PATENT OFFICE.

BURT D. STEVENS, OF EVANSTON, ILLINOIS, ASSIGNOR OF THREE-FOURTHS TO WILLIAM V. KELLEY, OF CHICAGO, ILLINOIS.

CARBURETOR.

Application filed April 10, 1916, Serial No. 470,947. Renewed May 19, 1921.

My invention relates to means for atomizing combustible liquids, such, for instance, as fuel feeding means for internal combustion engines and has particular reference 5 to novel mechanism adapted to the feeding of the high boiling point hydrocarbons to an engine in such manner as to insure complete combustion and consequent high efficiency. More accurately stated, the invention relates to simple and novel means for atomizing or treating hydrocarbons in a manner such that when the treated hydrocarbons are presented to air in proper proportions a combustible mixture is provided 10 which will insure complete combustion.

As is well known, the hydrocarbons having a boiling point higher than that of gasoline, and particularly kerosene, are highly efficient when properly treated prior to their 20 combustion. Kerosene does not vaporize at normal temperatures and difficulty has been experienced in sub-dividing the same to an extent sufficient to form an explosive mechanical mixture of hydrocarbon and air. 25 In the present mechanism I have provided not only for the heating of the hydrocarbon to assist in vaporization, but for the minute sub-division of the hydrocarbon and the delivery of the same into the incoming current 30 of air in the form of a mist or extremely fine spray. The result is secured by providing two co-acting members having flat surfaces and being in substantial contact, one of which members is adapted to be rotated at a high speed, the hydrocarbon being 35 delivered at substantially the axis of rotation of said member. Inasmuch as the surfaces of the relatively rotatable members are substantially in grinding engagement with 40 each other, it will be seen that the only hydrocarbon delivered at the periphery is delivered by centrifugal force and is sprayed or delivered in the form of a mist or fog. Preferably also the stationary member is 45 heated by an electrical resistance element. In the preferred embodiment of the invention the speed of rotation of the rotatable member and the heat applied to assist in vaporization are varied in direct proportion 50 to the throttle opening or, in other words, to the power required. Preferably also means are provided for heating the resistance element prior to the starting of the engine and independently of the operation 55 of the motor.

The invention will be more readily understood by reference to the accompanying drawings, wherein—

Figure 1 is a section through a carburetor or oil-feeding device constructed in accordance with my invention, and

Figure 2 is a diagrammatic outline of the wiring arrangement contemplated by me.

In the drawings, it will be seen that I have provided a casing 10, within which a 65 throttle 11 is mounted. The outlet 12 on the casing is connected to the intake manifold of the engine. The inlet 13 provides for the entrance of atmospheric air. Mounted in the entrance and supported by the cap 14, 70 is a stationary disc 15, having therein a plurality of resistance wires 16. A fuel supply pipe 17 terminates at the axis of the disc 15. Superposed on the disc 15 is a disc 18, rigidly secured to the armature shaft 19 75 of a motor 20. The armature shaft 19 is supported in bearings 19^a and 19^b so as to permit a slight amount of longitudinal movement of said shaft. The arrangement is such that hydrocarbon fed by gravity to 80 the pipe 17 is held against escape by the co-operation of the flat surfaces of the discs 15, 18. However, when the engine is in operation the motor 20 is rapidly rotating the disc 18 and the liquid between the discs, under the weight of disc 18 and parts thereabove, is in effect given a grinding treatment and thereby pressed toward the periphery of the discs and is delivered at the periphery in the form of a mist or very fine 85 spray. The heat supplied by the resistance element reduces the viscosity of the hydrocarbon and also results in the formation of a product which will readily atomize and which will combine with the air entering 90 through the inlet 13 to form an explosive mixture. It will be observed that the shaft 19 is so supported that it is capable of slight vertical movement through its bearings, consequently the weight of the motor 20 yielding 95 forces the disc 18 into contact with the disc 15. The liquids when drawn between the two relatively rotating discs 15 and 18, is consequently subjected to pressure and flattened into a thin film which serves to promote atomizing of the liquid as it is discharged around the peripheries of 100 the discs.

The arrangement as shown in Figure 2 is the preferable one for operation of the 110

device and is one wherein the throttle 11 is connected by means of a lever 21 to an operating rod 22. A link 23 connects the throttle lever to a yoke 24, which controls simultaneously the rheostats 25, 26. These rheostats control respectively the motor 20 and the heating element 16, the amount of current supplied to each being in direct proportion to the extent of throttle opening; that is, as the motor runs faster more current is supplied to the resistance unit. To assist in starting, I may provide the hand switch 27, which completes the circuit through the resistance element and heats the stationary disc 15 prior to the beginning of the fuel feeding operation. The control of the amount of fuel which is to be fed may be effected both by the extent of the amount the rotating disc is permitted to move above the fixed 20 plate and by pressure exerted between the discs and by the speed of the motor, and while it may not be found essential in some types of engine to vary the speed of the motor according to the extent of opening of the 25 throttle, such arrangement is thought to be desirable.

The mechanism herein shown is more or less diagrammatic in form, no attempt having been made to follow a strict design. Obviously, therefore, the invention is not limited to the form or arrangement of the parts except as indicated in the appended claims, and while I have illustrated my invention as embodied in fuel feeding means for oil burning engines, yet it will be understood that my invention is adapted for use wherever it may be desired to employ atomized combustible liquids.

I claim:

- 40 1. In a carburetor, the combination of a casing having inlet and outlet openings, a throttle valve near said outlet opening, fuel feeding means near said inlet opening, said last-named means including a plate, means for supplying heat to said plate, means for supplying the liquid to said plate at a point near the axis thereof, a rotatable member having a surface adapted to bear against said plate and to be separated therefrom, means for rotating said rotatable member at a variable speed, and means connected to said throttle valve to regulate the speed of the rotating member.
- 45 2. In a carburetor, the combination of a casing having air inlet and outlet openings, a throttle valve, a plate disposed within said casing, means for heating said plate, means for supplying the fluid fuel to the center of said plate, a disc having a surface adapted to bear against said plate, a motor for ro-

tating said disc, and means connecting said throttle, motor and heating means whereby, as said throttle is opened, the speed of said motor is increased and the heating capacity of said heating unit is likewise increased, substantially as described.

3. In a device for carbureting air, the combination of a plurality of members, one relatively movable with respect to the other, means whereby one is floatably mounted with respect to the other, and said members substantially having surface contact whereby a hydrocarbon fed therebetween is subjected to a grinding action for dividing same into finely divided particles preparatory to forming a combustible mixture, and means for feeding hydrocarbon between said members.

4. In a device for carbureting air, the combination of a plurality of members, one rotatably movable with respect to the other, means whereby one is floatably mounted with respect to the other, and said members substantially having surface contact whereby a hydrocarbon fed therebetween is subjected to a grinding action for dividing same into finely divided particles preparatory to forming a combustible mixture, and means for feeding hydrocarbon between said members.

5. In a device for carbureting air, the combination of a plurality of members, one relatively movable with respect to the other, means whereby one is floatably mounted with respect to the other, and said members substantially having surface contact whereby a hydrocarbon fed therebetween is subjected to a grinding action for dividing same into finely divided particles preparatory to forming a combustible mixture, means for feeding hydrocarbon between said members, and means whereby the relative speed of said relatively movable members may be varied for varying the effect of dividing the particles.

6. In a device for carbureting air, the combination of a plurality of members, one relatively movable with respect to the other, means whereby one is floatably mounted with respect to the other, and said members substantially having surface contact whereby a hydrocarbon fed therebetween is subjected to a grinding action for dividing same into finely divided particles preparatory to forming a combustible mixture, means for feeding hydrocarbon between said members, and means for heating one of said relatively movable members for facilitating the dividing of the particles.

Signed at Chicago, Illinois, this 7th day of April, A. D. 1916.

BURT D. STEVENS.
